UNITED STATES PATENT OFFICE.

JOHN H. GERKEN AND LOUIS HEBENSTREIT, OF PITTSBURG, KANSAS.

DETACHABLE CALK.

1,104,417.

Specification of Letters Patent. Patented July 21, 1914.

Application filed January 16, 1914. Serial No. 812,436.

To all whom it may concern:

Be it known that we, JOHN H. GERKEN and LOUIS HEBENSTREIT, citizens of the United States, residing at Pittsburg, in the county 5 of Crawford and State of Kansas, have invented a new and useful Improvement in Detachable Calks, of which the following is a specification.

This invention relates to detachable horse-10 shoe calks and especially to the means employed for locking said calks in position.

The invention consists of the novel features of construction hereinafter described, pointed out in the claims and shown in the 15 accompanying drawings, in which:

Figure 1 is an inverted plan view of a horse-shoe provided with our calks. Fig. 2 is a side elevation of the shoe, a locking device being shown in open position in dotted 20 lines. Fig. 3 is a section on the line 3—3 of Fig. 1, the calk being unlocked. Fig. 4 is a section on the line 4—4 of Fig. 1.

In these drawings 1 represents a horse-shoe provided with a toe boss 2 and heel 25 bosses 3. The toe boss is provided with a transversely extending wedge shaped and dovetail slot 4, and the heel bosses are provided with similar longitudinally extending slots 5. A toe calk 6 is adapted to be fitted 30 into the slot 4, and heel calks 7 are provided with shanks 8 which extend into the slots 5.

These calks may be of any desired form and while the toe calk is of a slightly different shape from the heel calks the locking 35 means which is the essential feature of this invention is the same for all of the calks. Each calk has provided in its shank portion a transverse groove 9 and extending from the inner end of the shank is an integral 40 metal strip 10, which is bent back upon the shank and is then bent inwardly to form a head 11 which is adapted to be driven into the groove 9. The strip 10 increases in width from the shank to the head so that 45 the head 11 is of greater length than the

groove 9 and when driven into said grooves the said heads project beyond the ends of the grooves and bear against the inner faces of the bosses, thereby preventing withdrawal of the calks until said heads have been again 50 forced out of the grooves 9.

By means of this construction we provide detachable calks each of which carries its own locking device, and it is unnecessary to hunt up screws, bolts or keys in order to lock 55 a calk in position.

What we claim is:—

1. The combination with a horse-shoe having dovetail bosses, of calks having shanks adapted to fit said bosses, said shanks being 60 transversely grooved, and integral metal strips carried by said shanks and bent back upon the shanks, the free ends of said strips coöperating with said grooves, the end portions of the strips having a width exceeding 65 the length of the grooves.

2. The combination with a horse-shoe calk, of a shank having a transverse groove therein, a comparatively thin metal strip carried by the end of the shank and bent back over 70 the shank, said strip having its free end bent inwardly and adapted to enter said groove, the said end portion having a width greater than the length of the groove.

3. The combination with a horse-shoe having 75 a boss provided with a dovetail slot, of a calk having a shank adapted to enter said boss, said shank being transversely grooved, said groove resting immediately adjacent the inner face of the boss when the shank is in 80 position, and means formed integral with said shank for entering said groove, said means having a greater width than the length of the groove.

JOHN H. GERKEN.
LOUIS HEBENSTREIT.
